(57) **CLAIM**

The ornamental design for a foldable plastic stand with slots, as shown and described.

DESCRIPTION

FIG. 1 is a front view of the foldable plastic stand with slots shown in a first position of use.

FIG. 2 is a back view of FIG. 1.

FIG. 3 is a front perspective view of FIG. 1 shown in a second position of use.

FIG. 4 is a perspective view of the left side of FIG. 3.

FIG. 5 is a perspective view of the back side of FIG. 3.

FIG. 6 is a perspective view of the right side of FIG. 3.

FIG. 7 is a bottom view of FIG. 3.

FIG. 8 is a front view of a foldable plastic stand with slots according to a second embodiment, shown in a first position of use.

FIG. 9 is a back view of FIG. 8.

FIG. 10 is a front perspective view of FIG. 8 shown in a second position of use.

FIG. 11 is a perspective view of the left side of FIG. 10.

FIG. 12 is a perspective view of the back side of FIG. 10.

FIG. 13 is a perspective view of the right side of FIG. 10; and,

FIG. 14 is a bottom view of FIG. 10.

The broken lines in the drawings are for the purpose of illustrating portions of the foldable plastic stand with slots which form no part of the claimed design.
